(57) CLAIM

The ornamental design for a cosmetic container as shown and described.

DESCRIPTION

FIG. 1 is a front perspective view of a first embodiment of the cosmetic container.

FIG. 2 is a front elevation view of the cosmetic container of FIG. 1.

FIG. 3 is a rear elevation view of the cosmetic container of FIG. 1.

FIG. 4 is a right side view of the cosmetic container of FIG. 1.

FIG. 5 is a left side view of the cosmetic container of FIG. 1.

FIG. 6 is a top view of the cosmetic container of FIG. 1.

FIG. 7 is a bottom view of the cosmetic container of FIG. 1.

FIG. 8 is a front perspective view of a second embodiment of the cosmetic container; and,

FIG. 9 is a right side view of the cosmetic container of FIG. 8.

The front elevation, rear elevation, left side, top and bottom views of the second embodiment of the cosmetic container are identical to the corresponding views of the first embodiment of the cosmetic container.

The appearance of any portion of the cosmetic container shown with dashed lines forms no part of the claimed design.

1 Claim, 6 Drawing Sheets
